NORMAN L. SNOW, OF NEW CANAAN, CONNECTICUT, AND SAMUEL F. COX, OF DETROIT, MICHIGAN, ASSIGNORS TO DIAMOND POWER SPECIALTY CORPORATION, OF DETROIT, MICHIGAN, A CORPORATION OF MICHIGAN

BOILER CLEANER

Original application filed February 9, 1925, Serial No. 8,082. Divided and this application filed January 22, 1927, Serial No. 162,739. Renewed January 28, 1931.

The invention relates to boiler cleaners and has among its objects to provide means for discharging one or more jets of cleaning fluid adjacent parts of the boiler to be cleaned.

5 A further feature of the invention resides in novel means for controlling and operating a boiler cleaner in connection with a locomotive, or other power plant.

This application is a division of our co-10 pending application, Serial Number 8,082, filed February 9, 1925.

Referring to the drawings:

Figure 1 is a side elevational view of a locomotive showing applied thereto somewhat 15 diagrammatically, our device for controlling the operation of a blower from a moving part of the locomotive;

Figure 2 is a diagrammatic fragmentary horizontal view partly in section through one 20 of the side water legs of the locomotive showing the boiler cleaner in projected operative position;

Figure 3 is an elevation partly in section showing the means for actuating the boiler 25 cleaner;

Figure 4 is a view partly in section through 4-4 of Figure 3;

Figure 5 is a horizontal fragmentary section showing the retracting means for the 30 blower, the blower being shown in projected position;

Figure 6 is an elevation of the reduction gearing operating the valve control mechanism;

35 Figure 7 is a plan thereof;

Figure 8 is a plan view of a detail of a modified construction for actuating a plurality of blowers, and

40 Figure 9 is an elevation of the same showing the cleaning fluid supply pipes and valves therefor.

In the drawings reference character A represents a locomotive of suitable construction, which as shown in Figure 2 is ordinarily provided with tube sheet 20, boiler tubes 21, and the side walls or water legs 22, one of which is shown in Figure 2. C indicates a boiler cleaner unit or blower element housed in a sleeve 23 extending through the water leg 22. Cleaning fluid from any suitable source

may be supplied to the blower as by a pipe 26, the supply of cleaning fluid being controlled as hereinafter described. It is preferred to provide a boiler cleaner unit in each of the side wall water legs 22, each blower being 55 preferably constructed as shown in Figures 3, 4 and 5. The pipe 26 has a branch 32 terminating in a nozzle 33 for directing a jet of cleaning fluid against the blades of a turbine rotor 34 keyed to shaft 35, the latter being 60 mounted in the reduction gear housing D. 36 is a shaft upon which is mounted a gear 37 driven by the turbine rotor 34 through suitable reduction gearing E. The shaft 36 carries a worm 38 meshing with worm wheel 39 which is provided with a sleeved portion 40 having a splined connection with a shaft 41 by reason of the pin 42 engaging the slot 43 of the shaft.

The cleaning fluid supply pipe 26 communicates with a chamber 44 of a fixed blower housing 45 mounted within the sleeve 23. This sleeve 23 may be expanded into the water leg of the locomotive boiler. The blower C comprises a slidable part 46 and a slidable 70 and rotatable blower head 47, the part 46 having a pin 48 slidable in a slot 49 of the fixed housing. The part 46 also has a port 50 adapted to successively register, as the blower head 47 is rotated by shaft 41, with a plurality 75 of passages 51 each of which terminates in a nozzle 52. The nozzles are directed at different angles so that as they are successively brought to register with the port 50, cleaning fluid will be directed in successively advancing jets of cleaning fluid across the tube sheet of the locomotive for substantially half the width of the tube sheet, it being understood that where two blowers are used the blower 80 on the opposite side will clean the other half 85 of the tube sheet.

Projecting from housing 45 are a plurality of guide pins 53 upon which is slidably mounted a plate 54 normally urged rearwardly by springs 55. The rear of shaft 41 is provided with a collar 56 pinned at 57 with the shaft 41. A thrust bearing 58 is provided for taking up the thrust produced by the cleaning fluid acting to project the blower C. 95 100

Suitably supported or suspended as by brackets 60 from a convenient part of the locomotive as the running board 59 is a gear box F, which contains a gear 61 mounted on a shaft 62. 63 indicates a shaft carrying a disc 64, the shaft 63 being actuated from the gear 61 through a suitable train of reduction gears G. Upon the disc 64 is a cam 65 in the path of which is a valve stem 66 carrying a valve disc 67. The valve disc 67 controls the passage of cleaning fluid from a main supply pipe 68, connected with a suitable source of cleaning fluid such as the steam dome 69, to the supply pipe 26. H indicates the fitting which encloses the valve 67 and connects the pipes 68 and 26. A spring 70 normally holds the valve 67 upon its seat 71 to prevent the passage of cleaning fluid from the main supply pipe 68 to the pipe 26. 72 is a rocker arm which may be rockingly supported at 73 to a convenient part of the locomotive. Connected at 74 with the rocker arm 72 is a dog 75 which engages the teeth on gear 61 to actuate the same. The rocker arm may be 25 rocked by connecting it with any suitable moving part of the locomotive as, for example, the rocker arm may be connected at 63 with the main locomotive valve actuating mechanism J.

30 If preferred, a blower unit may be located on either side of the locomotive, the mechanism shown in Figure 1 being duplicated on the other side, or if preferred, a single blower may be employed of suitable capacity for 35 cleaning all of the parts desired; or a blower may be located in each of the side wall water legs of the locomotive both blowers being controlled by mechanism on only one side of the locomotive. To the latter end the mechanism as described above may be modified 40 as shown in Figures 8 and 9. In these views the disc 64' is formed with a pair of cams 65^a and 65^b which rotate in separate planes and are adapted to successively engage the 45 valve stems 66^a and 66^b of the fittings H^a and H^b respectively to unseat the valves 67^a and 67^b. The valve 67^a, upon being unseated by contact of the cam 65^a with the valve stem 66^a admits cleaning fluid from the supply 50 pipe 68' to the pipe 26^a which supplies cleaning fluid to one of the blowers on the side of the locomotive. The disc 64' may be actuated in a manner corresponding to the mechanism described for operating the disc 64 and the blowers may also be similar to that shown in Figures 3, 4 and 5. As the disc 64' rotates, the cam 65^a will pass beyond the valve stem 66^a to permit the valve 67^a to be seated under the influence of spring 70^a, thus shutting off the supply of cleaning fluid from the supply pipe 68' to the pipe 26^a. The cam 65^b will then actuate the valve stem 66^b to unseat the valve 67^b against the action of spring 70^b, thus establishing communication between the supply pipe 68' and

the pipe 26^b leading to the blower on the side of the locomotive opposite to that communicating with the pipe 26^a.

By arranging suitable gearing at G, one revolution of the disc 64 or 64' may be made to correspond to any number of miles of travel of the locomotive so that the tube sheets, tubes or other parts of the locomotive boiler can be cleaned every time the locomotive travels a predetermined distance. The cams 65, or 65^a and 65^b, may be suitably shaped to give the performance of the blowers as desired. For example by increasing or decreasing the circumferential face of the cams, the period of blowing may be increased or decreased. The valve stems 66, or 66^a and 66^b, will be actuated slowly or quickly depending on how steep the radial faces of the respective cams are, as will be readily understood.

After a predetermined distance has been travelled by the locomotive, the rocker arm 72 will have actuated the dog 75 and gear 61 so that the disc 64 will have been rotated sufficiently to cause the cam 65 to act upon the valve stem 66 to unseat the valve 67 as shown in Figure 6, thus supplying cleaning fluid from the main supply pipe 68 to the pipe 26 and thence to the blower such as shown in Figures 3, 4 and 5. As the disc 64 continues to slowly rotate, the cam 65 will be carried beyond the point of engagement of the cam and valve stem 66, whereupon the spring 70 will return the valve 67 to its seat and cause the blower to be retracted to its inoperative position. Likewise, the blower on the opposite side of the locomotive will function in any predetermined time relation every time the locomotive has travelled a predetermined distance.

With references to Figures 8 and 9, in which the actuating mechanism for the blowers is entirely located on one side of the locomotive, the disc 64' first actuates one of the valve stems, as 66^a by contact with the cam 65^a, and preferably after the blower communicating with pipe 26^a has functioned, the cam 65^b acts to unseat valve 67^b to cause the other blower connected with 26^b to function.

The blowers C are normally housed within the respective sleeves 23 and thus protected from the heat of the fire chamber. Upon admission of cleaning fluid to the pipe 26 the blower is automatically projected forwardly under the influence of the cleaning fluid and against the action of the spring 55 into the position shown in Figure 4. Thus the blower head 47 and part 46 are projected forwardly, the latter part being guided by the engagement of the pin 48 with the slot 49. The rod 41 carrying the blower head is also projected forwardly toward the fire box, carrying also the plates 54 and compressing springs 55, the thrust bearing 58 absorbing the force of the thrust. The shaft 41 has splined engagement

at 42, 43 with the worm wheel 39, whereby the worm wheel can actuate the shaft 41 in its projected position. Cleaning fluid supplied through pipe 26 passes through the chamber 44 and thence to the stationary port 50 for successively supplying cleaning fluid to the passages 51 as they are selectively brought into registration with port 50.

Simultaneously with the projection of the blower, cleaning fluid passing through pipe 26 and branch pipe 32 is ejected from nozzle 33 to act upon the turbine 34 to cause rotation of shaft 35. The latter shaft, through the reduction gearing E, serves to rotate the shaft 36 carrying the worm 38 which in turn actuates shaft 41 to rotate the blower head 47 relatively to the part 46. Thus cleaning fluid is successively supplied to the nozzles 52 which by reason of their varying angularity, cause jets of cleaning fluid to sweep the tube sheet so as to trace lines across the tube sheet advancing to substantially midway of the tube sheet, where two blowers are employed. By proportioning the relative circumferential length of the port 50 and passages 51 the cleaning fluid may be admitted and cut off at the desired point so as to restrict the jet of cleaning fluid to the parts of the boiler to be cleaned. When the supply of cleaning fluid to pipe 26 is cut off the springs 55 act on plate 54 and shaft 41 to return the blower within the sleeve 23.

While we have shown our invention applied to locomotive power plants it should be understood that the invention is in no manner confined thereto, as the performance of a blower unit used in connection with stationary power plants may be likewise caused to automatically function after a predetermined movement of convenient moving part associated with the power plant. Furthermore, instead of employing blower units of the construction shown in Figures 3, 4 and 5, it is obvious that any other suitable construction of blower unit might be substituted therefor. Also, if desired, both of the blowers described, or any number of blowers could be operated simultaneously or in any sequence preferred.

50 What we claim as our invention is:

1. In combination with a locomotive having a part continuously movable during the operation thereof, a boiler cleaner unit for cleaning parts of the boiler, and means associated with the said moving part for periodically causing the said unit to function to clean the said parts of the boiler.

2. In combination with a locomotive, a boiler cleaner therefor, and means operable upon a predetermined travel of said locomotive for automatically operating the boiler cleaner.

3. A boiler cleaner for locomotives, comprising a blower unit, a source of cleaning fluid, means for controlling the supply of

said fluid from the source to the blower unit, and means automatically responsive to a predetermined distance travelled by the locomotive for acting upon said cleaning fluid control means to admit cleaning fluid to the blower unit.

4. In combination with a locomotive, a boiler cleaner unit therefor, a member movable during the travel of said locomotive and means responsive to a movement of said member for causing the unit to function to clean parts of the locomotive.

5. In combination with a locomotive, a boiler cleaner unit therefor, and means responsive to a predetermined travel of the locomotive for periodically causing the unit to function to clean parts of the locomotive.

6. In combination with a locomotive having a part movable in time relation to the travel of the locomotive and having a side wall water leg, a source of cleaning fluid, a blower unit housed within the water leg, a valve controlled source of cleaning fluid communicating with the blower, and means actuated by said moving part for periodically acting to unseat the valve to supply cleaning fluid to the blower.

7. In combination with a locomotive, a boiler cleaner unit therefor, a source of cleaning fluid, a valve for controlling the supply of cleaning fluid from said source to said unit, gearing including a cam member, means extending in the path of the cam and connected to unseat said valve, and means actuated by a moving part of the locomotive for operatively engaging said gearing whereby the valve is periodically unseated to supply cleaning fluid to said boiler cleaner unit.

8. In combination with a locomotive, a boiler cleaner unit therefor, a source of cleaning fluid, a valve for controlling the supply of cleaning fluid from said source to said unit, a rocker arm connected to receive movement from a moving part of the locomotive, a dog reciprocated by said rocker arm, reduction gearing including a gear actuated by said dog and a cam, means located in the path of the cam and connected to unseat said valve whereby said valve is automatically and periodically unseated to supply cleaning fluid to the cleaner unit.

9. In combination with a locomotive, a rotatable blower unit, a member movable in timed relation to the travel of said locomotive, a supply of cleaning fluid, and means controlled by said member for periodically rotating said blower unit and admitting cleaning fluid from said supply to said blower.

10. In combination with a locomotive, a boiler cleaner unit, a member movable in timed relation to the travel of the locomotive, a supply of cleaning fluid, a prime mover for moving said unit, and means controlled by said member for periodically ad-

mitting cleaning fluid to said unit for cleaning parts of the boiler, said control means also acting to cause operation of the prime mover.

5 11. In a locomotive, having a valve gear and a boiler, a blower cleaner unit, a source of cleaning fluid, and means responsive to movement of the valve gear for periodically acting to supply cleaning fluid from said

10 source to said cleaner unit.

12. In combination with a locomotive having a side wall water leg and a movable part associated with the locomotive, a source of cleaning fluid, a rotatable projectible blower unit normally housed within the said water leg, a valve controlling the supply of cleaning fluid from said source to said blower unit, reduction gearing including a cam member, means extending in the path of the cam, and 15 connected to unseat the valve, means for transmitting motion from said movable part of the locomotive to said reduction gearing for causing said cam to periodically unseat the valve whereby cleaning fluid is supplied 20 to project and rotate the blower.

13. In combination with a locomotive having side wall water legs, a blower unit located in each of said water legs, a source of cleaning fluid, and means actuated by a moving part of the locomotive after the locomotive 25 has travelled a predetermined distance for supplying cleaning fluid selectively to said blowers.

14. In combination with a locomotive having side wall water legs, a blower unit located in each of said water legs, a source of cleaning fluid, reduction gearing including a cam carrying element, a plurality of cams on 30 said element, valves for controlling the supply of cleaning fluid to said blowers respectively, means operatively connected with said valves and projecting in the paths of said cams respectively, to effect an actuation of said valves from said cams, means actuated by a moving part of the locomotive after 35 the locomotive has travelled a predetermined distance for acting on said reduction gearing to cause said cams to successively unseat said valves to supply cleaning fluid to said blowers respectively.

15. In combination with a locomotive having a side wall water leg, a projectible blower unit, normally located within the water leg, a source of cleaning fluid, and means operable upon a predetermined travel of the locomotive for periodically admitting cleaning fluid from said source to said blower for projecting the same into operative position.

16. In combination with a locomotive having side wall water legs, a blower unit slidably housed in each of said water legs, a source of cleaning fluid, and means operable upon a predetermined travel of the locomotive for periodically admitting cleaning fluid 50 from said source selectively to said blow-

ers for projecting them into operative position.

17. The method of operating and cleaning a locomotive boiler consisting in providing a supply of cleaning fluid and blowing the 70 cleaning fluid adjacent parts of the boiler to be cleaned periodically depending on a predetermined distance travelled by the locomotive.

18. The combination with a locomotive 75 having a member movable in a predetermined relation to the travel of the locomotive, of a boiler cleaner unit, and means dependent upon the movement of said member for actuating said unit.

19. The combination with a locomotive having a member movable in a predetermined relation to the travel of the locomotive, of a boiler cleaner unit, and a connection between 80 said member and said unit for actuating said unit in timed relation to the travel of the locomotive.

20. The combination with a locomotive having a member movable in a predetermined relation to the travel of the locomotive, of a 90 boiler cleaner unit, and means dependent upon the movement of said member for actuating said unit, said means including a cam actuated by said member and a valve actuated by said cam for controlling the supply of 95 cleaning fluid to the said unit.

21. The combination with a locomotive having a part movable in responsive to the operation of the locomotive, of a boiler cleaner unit for cleaning parts of the boiler, and 100 means actuated by the said moving part for automatically controlling the operation of the said boiler cleaner unit.

22. The method of cleaning a locomotive boiler which consists in effecting a removal 105 of the deposits from those surfaces of the boiler exposed to the products of combustion periodically in dependence upon the distance travelled by the locomotive.

23. The method of cleaning a locomotive 110 boiler which consists in effecting a removal of the deposits from those surfaces of the boiler exposed to the products of combustion periodically in dependence upon the operation of the locomotive.

24. The method of cleaning a locomotive boiler which consists in discharging cleaning fluid adjacent portions of the boiler to be cleaned periodically in dependence upon the operation of the locomotive.

25. The combination with a locomotive, of means operable upon a predetermined operation of the locomotive to effect a removal of the deposits from the surfaces of the boiler of the locomotive exposed to the products of combustion.

26. The combination with a locomotive having a part movable in response to the operation of the locomotive, of means actuated by said moving part for effecting a removal of 130

the deposits from those surfaces of the boiler of the locomotive exposed to the products of combustion.

27. The combination with a locomotive having a part movable in response to the operation of the locomotive, of a plurality of boiler cleaner units for cleaning parts of the locomotive boiler, and means actuated by the said moving part for automatically controlling the operation of the said boiler cleaner units.

28. The combination with a locomotive having a valve gear operable upon travel of the locomotive, of a plurality of boiler cleaner units for cleaning parts of the locomotive boiler, and means controlled by the movement of said valve gear for periodically effecting an actuation of said boiler cleaner units.

29. The combination with a locomotive, of a rotatable boiler cleaner therefor, means for rotating said boiler cleaner, means for supplying cleaning fluid to said boiler cleaner, and means operable upon a predetermined travel of the locomotive for automatically effecting an actuation of said rotating means.

30. The combination with a locomotive, of a rotatable and projectile boiler cleaner therefor, said boiler cleaner being provided with a plurality of discharge nozzles for directing jets of cleaning fluid adjacent portions of the locomotive boiler to be cleaned, means for controlling the flow of cleaning fluid to said nozzles in dependence upon the rotation thereof, means for rotating said nozzles, and means for controlling the actuation of said rotating means and the supply of cleaning fluid to said boiler cleaner in dependence upon the distance traveled by the locomotive.

31. The combination with a locomotive, of a plurality of boiler cleaners therefor, a rotatable member, means for periodically rotating said member in dependence upon the distance traveled by the locomotive, and means actuated by said rotatable member for controlling the operation of said boiler cleaner units.

32. The combination with a locomotive, of a plurality of boiler cleaners therefor, and means operable upon a predetermined travel of said locomotive for automatically successively operating the said boiler cleaners.

33. The combination with a locomotive having a part movable in timed relation to the travel of the locomotive, of a plurality of boiler cleaners for the locomotive, means including a valve associated with each boiler cleaner for controlling the operation of said boiler cleaners, a rotatable member provided with a plurality of cams for actuating said valves, and connections between said rotatable member and the moving part of said locomotive for rotating said rotatable member in timed relation to the travel of the locomotive.

34. In combination, a locomotive, a plurality of boiler cleaners therefor, and means for successively effecting an actuation of said boiler cleaners in dependence upon the distance traveled by the locomotive, said means including a cam member movable in timed relation to the travel of the locomotive, and a plurality of cams on said cam member for controlling the actuation of said boiler cleaners.
